W. W. MOCK

APPARATUS FOR MAKING GRITLESS CARBONIFEROUS PRINTING INKS

Original Filed Feb. 8, 1922

Walter W. Mock,
Inventor.

By His Attorney,
Hewitt.

UNITED STATES PATENT OFFICE.

WALTER W. MOCK, OF RUTHERFORD, NEW JERSEY.

APPARATUS FOR MAKING GRITLESS CARBONIFEROUS PRINTING INKS.

Application filed February 8, 1922, Serial No. 534,874. Renewed November 22, 1923.

To all whom it may concern:

Be it known that I, WALTER W. MOCK, a citizen of the United States, residing at Rutherford, in the county of Bergen and State of New Jersey, have invented new and useful Improvements in Apparatus for Making Gritless Carboniferous Printing Inks, of which the following is a specification.

10 This invention relates to an improved centrifugal apparatus suitable for use in the production of so-called gritless printing inks, particularly of the type known as web press or news inks, and has for its principal 15 objects the provision of a machine which is capable of expeditiously and economically separating gritty crystalline carbon particles from carbon-containing inks and especially from such inks in which the original carbon content comprises substantial quantities of such carbon particles.

I am aware that it has been proposed to clarify varnishes and the like by the employment of so-called centrifugal clarifiers 20 but such machines are not adapted for use without modification for the purpose of effectively separating the so-called gritty crystalline carbon particles contained in ordinary printing inks from the amorphous 25 or non-gritty particles, owing to the fact that the specific gravities of amorphous carbon and crystalline carbon so closely approximate each other, which fact necessitates more effective control of the various features which 30 influence the character of the resultant product than is possible in centrifugal clarifiers such as have been heretofore constructed.

My investigations have led to the discovery of a centrifuge which is ideally 35 adapted for the treatment of carboniferous printing inks containing very substantial quantities of carbon particles, in order to practically eliminate such gritty crystalline carbon particles therefrom and to produce an ink which is remarkably free from gritty particles—containing less than one-quarter of one per cent of such particles—and which consequently eliminates the necessity for frequent cleaning of the plates, as is now 40 commonly required when employing ordinary carboniferous printing inks.

Referring to the drawings and the construction shown therein the reference numeral 1 designates a hollow standard in 45 which is mounted a vertical shaft 2 having a worm 3 adapted to be operated by a belt-

5 driven gear 4 in the well-known manner. A rotary bowl 5 keyed to the upper end of said shaft projects into an enlarged chamber α . Preferably, as shown, said bowl comprises 60 an outer shell 6 having a removable top-section 6', substantially conforming to a cone frustum, and having an outlet orifice 7. A supplemental bowl comprising a shell 8 and a removable bottom member 8' is 65 supported within said outer bowl and spaced sufficiently above the bottom of the latter to afford a passage 9 for liquid which escapes through the annular outlet 10 of said supplemental bowl. The neck 11 of said supplemental bowl is of sufficient size to receive an inlet conduit 12 and afford an annular overflow passage 13. Said conduit 12 is closed 70 at its lower end and provided with a narrow slot b which sprays liquid into the supplemental bowl at an angle to the axis thereof. 75

A super-structure of light construction, for example of tin, is fitted to the hollow standard above the chamber α and the same is partitioned into an upper chamber 14, two 80 intermediate chambers 16 and 17 and a fourth or bottom chamber 18. The upper chamber 14 is of sufficient height to afford an efficient working head for news ink delivered into the machine, for example in a machine 85 having a bowl with an outlet of $\frac{1}{2}$ sq. in. area. The top of said chamber is preferably 14 $\frac{1}{2}$ inches above the outlet orifice 7 of said bowl and its vertical wall is preferably 11 $\frac{1}{2}$ inches high. Within the neck 15 of this 90 chamber is fitted a strainer 19 for the removal of coarse particles. The chamber 14 is provided with an outlet orifice 20, preferably adjacent the top thereof, which is 95 adapted to discharge into a conduit 20' the ink which backs-up into the chamber 14 when the inner bowl overflows due to clogging or choking thereof by gritty particles of accumulated carbon which have been separated from the ink. The chamber 16 is 100 provided with an outlet orifice on its outer periphery which communicates directly with and is adapted to discharge into a conduit 21 the ink which backs-up into the chamber 14 when the inner bowl overflows 105 due to clogging or choking thereof by gritty particles of accumulated carbon which have been separated from the ink.

As shown, these discharge conduits 20', 21 serve to deliver such overflow which is 110 obviously incompletely treated ink, into a separate receptacle from that which receives

the discharge issuing from orifice 7 that is discharged into conduit 22 in communication therewith. The overflowing of the ink thru said conduits 20', 21 will serve to indicate that the accumulation of carbon in the inner bowl is so large as to interfere with the proper centrifuge separation and thereby will warn the operator against further operation of the machine until the

10 accumulated carbon has been removed.

While I have specified that preferably the top of the chamber 14 is 14 $\frac{1}{2}$ inches above the outlet orifice 7 of the outer bowl, it is obvious that the outlet orifice 20 may be 14 $\frac{1}{2}$ inches above the outlet orifice 7 and the super-structure may extend further above the outlet orifice 20 without changing the operation of the apparatus, since the chamber 14 could not be filled above its outlet

20 orifice. However, there would be no advantage in extending the top of the super-structure above its upper outlet orifice 20, as such an extension would be merely a waste of material without adding any increased function or capacity to the chamber 14. I do not wish to confine myself to the exact limits of 14 $\frac{1}{2}$ inches between the orifices 7 and 20, but for a bowl with an outlet of $\frac{1}{6}$ sq. in. area, when operating on

25 so-called news ink, the vertical distance therebetween should not be less than 11 $\frac{1}{2}$ inches nor more than 17 $\frac{1}{2}$ inches in order to obtain satisfactory results.

The operation of the aforesaid apparatus, 30 when utilizing the same for the production of gritless news ink is as follows:

News ink is prepared in the well-known manner by mixing about 10 parts of carbon-black with 90 parts so-called printers' varnish, the latter consisting essentially of lubricating oil, and then grinding the mixture in a mill. The prepared ink is then delivered into a suitable reservoir from which it is tapped through a pipe to the chamber 14. The prepared ink delivered to the chamber 14 should be preferably maintained between about 110° to 120° F. in order to insure a desirable degree of viscosity and prevent a minimum amount of the amorphous carbon particles from being expelled while effecting the expulsion from the mixture of crystalline carbon particles. The elevation of the top of the chamber 14 above the bowl to the extent above specified, 45 insures the maintenance of the proper pressure that is required to regulate the flow of the mixture into the bowl so that it will be subjected to centrifugal action therein a sufficient length of time to cause the gritty particles to be thrown out of suspension and yet an insufficient time to effect the expulsion of the amorphous particles. When operating upon a mixture such as the foregoing, the head of the liquid in the machine should 50 be such that the rate of flow, when the ma-

chine is running 4000 R. P. M., will be between 250 and 300 gallons per hour in a machine having a bowl with an outlet of $\frac{1}{6}$ sq. in. area.

The product delivered through the outlet 70 conduit 7 is remarkably free from gritty particles, notwithstanding the fact that the specific gravities of amorphous carbon and crystalline carbon very closely approximate each other. Apparently the aforesaid 75 centrifugal machine is capable of effecting this separation of the different carbon components of the mixture, not so much because of any difference in specific gravity between these two phases of carbon but rather because of the difference in the specific surfaces of the respective particles and in this respect is somewhat analogous to the phenomenon of the suspension of fine particles of clay in water simultaneously with the 80 sedimentation from the same medium of the coarser particles of clay that are of almost identical specific gravity therewith but of quite different specific surface.

In a machine of the capacity herein described 90 it is preferable that the area of the outlet orifice 7 of the bowl should approximate $\frac{1}{6}$ sq. in., this being a dimension which will give satisfactory results when operating on carboniferous news inks in a centrifuge 95 having a superstructure of the dimension described and the machine is rotating at approximately 4000 R. P. M.

Having thus described my invention, what I claim and desire to secure by U. S. Letters 100 Patent is:

1. In a centrifugal apparatus for making gritless carboniferous printing inks, the combination comprising a standard, a rotary bowl provided with an outlet orifice, a supplemental bowl mounted within said rotary bowl, a super-structure having a chamber of relatively large cross-section at its top and of reduced cross-section at its bottom, filtering means arranged in said bottom portion of said super-structure, outlet conduits 105 respectively connecting with the said enlarged top portion of said super-structure and with the reduced bottom portion of said super-structure respectively, the latter outlet 110 conduit connecting with the interior of said supplemental bowl and the height of such super-structure being sufficient to maintain such a head upon printing ink delivered into said supplemental bowl as to insure that 115 such ink will remain in at least one of the bowls of said apparatus a sufficient length of time to insure the expulsion of gritty carbon particles but an insufficient time to afford of the expulsion of amorphous carbon particles from said ink.

2. In a centrifugal apparatus for making gritless carboniferous printing inks, the combination comprising a standard, a rotary bowl provided with an outlet orifice, a sup- 130

- plemental bowl mounted within said rotary bowl, a super-structure having a chamber of relatively large cross-section at its top and of reduced cross-section at its bottom, filtering means arranged in said bottom portion of said super-structure, outlet conduits respectively connecting with the said enlarged top portion of said super-structure and with the reduced bottom portion of said super-structure respectively, the latter outlet conduit connecting with the interior of said supplemental bowl and the height of such super-structure being such that the distance between the outlet orifice of the enlarged top thereof is at least 12 inches above the outlet orifice of the outer bowl.
3. In a centrifugal apparatus for making gritless carboniferous printing inks, the combination comprising a standard, a rotary bowl provided with an outlet orifice, a supplemental bowl mounted within said rotary bowl, a super-structure having a chamber of relatively large cross-section at its top and of reduced cross-section at its bottom, filtering means arranged in said bottom portion of said super-structure, outlet conduits respectively connecting with the said enlarged top portion of said super-structure and with the reduced bottom portion of said super-structure respectively, the latter outlet
- conduit connecting with the interior of said supplemental bowl and the height of such super-structure being such that the distance between the outlet orifice of the enlarged top thereof is at least 14 inches above the outlet orifice of the outer bowl.
4. In a centrifugal apparatus for making gritless carboniferous printing inks, the combination comprising a standard, a rotary bowl provided with an outlet orifice, a non-rotatable super-structure extending to a substantial elevation above said bowl, an outlet orifice adjacent the top of said super-structure and an outlet orifice adjacent the bottom thereof, the height of such super-structure being such that the top outlet orifice thereof will be at least 12 inches above the outlet orifice of said outer bowl, whereby a sufficient head is afforded to viscous printing ink entering the bowl to allow of a sufficient time for the expulsion of gritty carbon particles but an insufficient time to allow of the expulsion of amorphous carbon particles from said ink when said bowl is rapidly rotated.
- Signed in New York city, in the county and State of New York, this 26 day of January, 1922.

WALTER W. MOCK.
